CASKET HARDWARE CORNER MEMBER

Lawrence L. Green, Elmwood Park, Ill., assignor to
Modern Metallics, Inc., Chicago, Ill., a corporation of
Illinois

Application July 6, 1959, Serial No. 56,656

Term of patent 7 years

(Cl. D19—2)

Fig. 1 is a perspective view of a casket hardware corner member, showing my new design;

Fig. 2 is a top plan view;

Fig. 3 is an end elevational view, the opposite end being substantially a mirror image thereof; and

Fig. 4 is a bottom plan view thereof.

The broken line fragmentary showing of a casket is for illustrative purposes only.

I claim:

The ornamental design for a casket hardware corner member, substantially as shown and described.
